US0D1109144S

(12) **United States Design Patent** (10) **Patent No.:** **US D1,109,144 S**
(45) **Date of Patent:** **** Jan. 13, 2026**

(54) **TABLET COMPUTER**

(71) Applicant: **Lenovo (Beijing) Limited**, Beijing (CN)

(72) Inventor: **Shoujin Wu**, Beijing (CN)

(73) Assignee: **Lenovo (Beijing) Limited**, Beijing (CN)

(**) Term: **15 Years**

(21) Appl. No.: **35/522,589**

(22) Filed: **Sep. 19, 2024**

(80) **Hague Agreement Data**

Int. Filing Date: **Sep. 19, 2024**

Int. Reg. No.: **DM/240690**

Int. Reg. Date: **Sep. 19, 2024**

Int. Reg. Pub. Date: **Oct. 11, 2024**

(30) **Foreign Application Priority Data**

Mar. 20, 2024 (CN) 202430144547.3

(51) **LOC (15) Cl.** **14-02**

(52) **U.S. Cl.**

USPC **D14/341**
